(57) **CLAIM**

The ornamental design for a handle for cylinders, as shown and described.

DESCRIPTION

FIG. 1 is a front, top perspective view of a handle for cylinders showing my new design in a position of use; FIG. 2 is a front, top perspective view of the handle with the cylinder removed and similar to FIG. 1; FIG. 3 is a rear, bottom perspective view of the handle; FIG. 4 is a front elevational view of the handle, the rear being a mirror image thereof; FIG. 5 is a right side, elevational view of the handle, the left side being a mirror image thereof; FIG. 6 is a top plan view of the handle; and, FIG. 7 is a bottom, plan view of the handle. The broken lines shown in the drawings illustrate the environment and portions of the handle for cylinders that form no part of the claim.

1 Claim, 4 Drawing Sheets
